UNITED STATES PATENT OFFICE

2,449,100

NEEDLE FRAME FOR GAUZE WEAVING LOOMS

Maurus Banyai, Glasgow, Scotland, assignor to
 M. Banyai Limited, Glasgow, Scotland, a corporation of Great Britain

Application May 21, 1946, Serial No. 671,270
 In Great Britain April 3, 1946

3 Claims. (Cl. 139—53)

1

This invention relates to improvements in needle frames for gauze weaving looms.

Needle frames used in gauze weaving looms are liable to produce defects in the fabric if, and when, the thickness of the warp yarn exceeds the normal thickness of the warp yarn used in the production of gauze, because the doup needles cannot bear closely against the dents of the frame due to the excessive thickness of the yarn therebetween.

According to the present invention, the eyelets in the free end portions of the doup needles are located exteriorly of the plane of the dents, i. e., spaced forwardly thereof, so that the elasticity of the yarn permits the free ends of the needles to bear against the dents. The free ends of the needles are therefore formed with forward bends and the eyelets are located at the bends of the needles so as to be in a line front of the dents.

The features of the invention are shown in the accompanying drawings forming a part of this application.

In the drawings:

Fig. 1 is a fragmentary front view of a needle frame for gauze weaving looms in which the features of the invention are shown in an illustrated manner.

Fig. 2 is a side view of the frame shown in Fig. 1.

Fig. 3 is an enlarged fragmentary sectional plan view taken on the line III—III of Fig. 1 and illustrating the action of the needles in connection with the position of the yarns and dents of the frame.

Referring to Figs. 1 and 2 of the drawings, 10 indicates the top cross-bar of the needle frame, 11 the bottom cross-bar and 12 one side of the frame. The dents of the frame are indicated at 13 as being mounted in the cross-bars 10 and 11, and 14 indicates the doup needles which alternate with the dents 13. In the structure as shown, the dents 13 are flat elements mounted parallel to each other in the usual manner between the cross-bars 10 and 11, while the doup needles, also flat elements, have their lower ends fixed and mounted in the cross-bar 11, so that they alternate between the dents 13.

The free ends of each needle 14 as shown in Fig. 2 is formed with a forward bend or tongue 15, the tip of which projects between adjacent dents 13. Each needle is provided with an eyelet 16 at its bend, the eyelets being located exteriorly of the plane of the frame or dents 13. In other words, the registering eyelets 16 are located in the bends 15 of the needles 14, so as to be in line in front of the dents 13 of the needle frame.

Fig. 3 illustrates the position of the yarns when

2

the tongues 15 of the needles 14 are pressed against the adjacent dents 13. It will be noted that the elasticity of the yarns Y extending through the eyelets 16 in front of the dents 13, and below the tongues 15 of the needles, permits these yarns to be pressed against the adjacent dents 13 so as to leave ample room for passage of the crossing yarns Z. The yarns Y are therefore not pressed between the tips of the needles 14 and the dents 13, as in previously known needle frames.

It is to be understood that the invention is not restricted to the particular form of bend illustrated for the needles 14.

15. What is claimed is:

1. In a needle frame for weaving looms including a row of spaced dents extending between cross-bars of the frame, and doup needles alternating with the dents of the frame, the improvement which comprises doup needles extending from one of the cross-bars and each terminating with a free end intermediate the cross-bars, the free end portion of each needle having an eyelet to one side of the row of dents, the eyelets of the needles being in register in a line to one side of the row of dents, and each needle having an offset tip end extending between adjacent dents and adapted to engage the adjacent sides thereof beyond and vertically spaced from the position of the eyelet in the needle, whereby a yarn extending through the eyelet and between adjacent dents is free of and in substantially the same vertical plane as the tip of the needle.

2. A needle frame as defined by claim 1 in which the portion of each needle at the position of its eyelet is spaced laterally from the adjacent dents and the tip of the needle includes a bent portion extending between adjacent dents.

3. A needle frame as defined by claim 1 in which the portion of each needle at the position of its eyelet is laterally spaced from the adjacent dents sufficiently for a yarn extending through the eyelet of the needle and between adjacent dents to pass around an edge of the needle and in front of an adjacent dent when the tip of the needle is in contact with said dent.

MAURUS BANYAI.
